US0D1098644S

(12) **United States Design Patent** (10) **Patent No.:** **US D1,098,644 S**
(45) **Date of Patent:** **** Oct. 14, 2025**

(54) **FRAME FOR PRESSURE WASHER**

(71) Applicant: **JD North America Corp.**, Ontario, CA (US)

(72) Inventor: **Paul Janik**, Saukville, WI (US)

(73) Assignee: **JD North America Corp.**, Ontario, CA (US)

(**) Term: **15 Years**

(21) Appl. No.: **29/887,483**

(22) Filed: **Mar. 21, 2023**

(51) **LOC (15) Cl.** **15-05**

(52) **U.S. Cl.**

USPC **D32/25**

(58) **Field of Classification Search**

USPC D15/7, 9; D23/213, 223, 224, 226; D32/1, 15, 16

CPC B05B 9/0426; B08B 3/02; B08B 3/026; B08B 3/028

(57) **CLAIM**

The ornamental design for frame for pressure washer, as shown and described.

DESCRIPTION

FIG. 1 is a perspective view of an frame for the pressure washer;

FIG. 2 is a front elevation view of the frame for the pressure washer of FIG. 1;

FIG. 3 is a rear elevation view of the frame for the pressure washer of FIGS. 1 and 2;

FIG. 4 is a first side elevation view of the frame for the pressure washer of FIGS. 1-3;

FIG. 5 is a second side elevation view of the frame for the pressure washer of FIGS. 1-4;

FIG. 6 is a top plan view of the frame for the pressure washer of FIGS. 1-5; and,

FIG. 7 is a bottom plan view of the frame for the pressure washer of FIGS. 1-6.

The broken lines in the figures illustrate environmental structures and portions of the design that form no part of the claimed design. The boundary lines shown in the drawings represent boundaries of the claimed design.

1 Claim, 7 Drawing Sheets
